UNITED STATES PATENT OFFICE

OTTO M. SUMMERS, OF DAYTON, OHIO, ASSIGNEE TO FRIGIDAIRE CORPORATION, OF DAYTON, OHIO, A CORPORATION OF DELAWARE

REFRIGERATING APPARATUS

Application filed May 30, 1928. Serial No. 281,600.

This invention relates to improvements in refrigerating apparatus, and more particularly to a control mechanism used for controlling the flow of refrigerating medium.

An object of this invention is to provide a control mechanism for controlling the flow of refrigerating medium which is rugged in construction and which is provided with means for preventing damage to the control mechanism during abnormal pressure conditions in the refrigerating apparatus.

Another object of this invention is to provide a refrigerating system including a controlling mechanism which is adapted to withstand abnormal pressures created in the system without damage to the parts of the controlling mechanism, or without disturbance of its calibration.

Further objects and advantages of the present invention will be apparent from the following description, reference being had to the accompanying drawings, wherein a preferred form of the present invention is hereby clearly shown.

In the drawings:

Fig. 1 is a side view in elevation of a control mechanism embodying features of my invention;

Fig. 2 shows a side cross-sectional view of the control mechanism with the device in the position immediately after the closing of the circuit;

Fig. 3 is a view similar to Fig. 2 showing the device when subjected to abnormal pressures and illustrating the means used to prevent damage to the device;

Fig. 4 illustrates a refrigerating system embodying features of my invention; and

Fig. 5 is a cross-sectional view along the line 5—5 of Fig. 3.

In the operation of refrigerating systems, for instance of the compressor-condenser-expander type such as is diametrically represented in Fig. 4, the refrigerating medium, for example sulphur dioxide, evaporates in an evaporator, indicated by 10 which, with the coils 11, constitutes the refrigerating element of the system. The refrigerant is supplied to the evaporator 10, in this particular embodiment, by means of a compressor 12

operated by a motor 15 which forces the refrigerant into condenser 13 and receiver 13a, whence it enters the evaporator 10 through pipe 14. It is withdrawn from the evaporator 10 through pipes 16 and 17 and is returned to the compressor, in this particular embodiment, through the crankcase. In order to control the operation of the compressor in accordance with the requirements of the refrigerating element, a control device is provided, which, for example, comprises a switch controlling the circuit of the motor used for driving the compressor. This switch, having contacts indicated by 17 and 18, is operated by means of a lever system 19 connected to a pressure responsive device such as a diaphragm or a bellows 20 connected to the refrigerating circuit.

In the construction of control devices of this type, in which a pressure-responsive element or container is used for operating the contacts, difficulty has been experienced because of damage to the expansible element caused by abnormal pressures, such as occur during shipping or storage of the refrigerating apparatus or system. When the system is in normal operation, the compressor periodically withdraws refrigerant from the evaporator 10 and prevents a rise in pressure above a certain normal limit. When the system is not in normal operation, as during shipment or storage, the compressor is not in periodic operation, and the refrigerating element or cooling unit warms up and creates a high pressure condition within the system. This pressure may build up to such an extent that it deforms the expansible member and causes it to take a definite permanent set. Damage may also be caused by straining of the switch actuating levers or other parts.

By means of the present invention, means is provided for preventing damage to the expansible member and to other elements of the switch. This means may comprise a mounting for a switch member upon a yielding platform or framework, the arrangement being so constructed and arranged that during the normal operation of the system, the switch acts in the ordinary manner, but

upon the occurrence of excessive pressures the yielding nature of the mounting prevents damage to the parts by relieving the strain caused by such pressures.

5 As a specific embodiment, the member for controlling the starting and stopping of a refrigerating system embodying features of my invention may be a switch having certain features shown in Figs. 1, 2, 3 and 5 inclusive. In general, the switch may comprise a base 100 provided with pedestals 101 for attaching the switch to any desired portion of the refrigerating system. A pressure-responsive element 20, such as a collapsible capsule or bellows, may be mounted on the base 100 and may be secured thereto by means of the nut 102 threaded on the portion 103 of the pipe 21. A reinforcing plate 104 may be placed under a portion of the base 100. In order to provide the abnormal pressure yielding means, an elevated platform 105 may be carried by the platform 100 and may be secured thereto by bolts 106 provided with spacing sleeves 107 for properly spacing the platform 105 from the base 100. The pressure-responsive element 20 operates the switch contacts, for instance, through a lever 22 by means of the link 25 which may be attached to the plate 23 which in turn may be attached to the upper end of the pressure-responsive element 20. A second platform 108 may be placed on top of the platform 105. This platform may be normally held in contact with the platform 105 by means of bolts 109 and springs 110 interposed between the platform 108 and the heads 109a of the bolts 109. If desired one end only of the platform 108 may be thus secured, and the other end may be secured by bolts 111 which permit only a slight play between the platforms 105 and 108. The strength of springs 110 is sufficient to maintain the platforms 105 and 108, together during normal operation.

45 A pivot may be provided for the lever 22. The pivot may be made by bending ears 28 upwardly from the platform 108. The pivot pin 29 may then be passed through the ears 28 and the lever 22.

50 Since pressure-responsive elements usually are not manufactured in quantities with the individual elements having the same resiliency, and in order to adjust the switch at any time, a resiliency adjustment may be provided. For this purpose a threaded rod 30 may pass through the arm 22 and through a sub-platform 31 made of insulating material and attached by bolts 31a to the platform 100. A disk 32 may be attached to the rod 30 and a spring 33 may be interposed between the disk 32 and the sub-platform 31. By properly tensioning the spring 33 the upward and downward movement of the arm 22 may be regulated to any desired extent.

55 A snap action may be provided for the arm 22, and in this specific embodiment may com-

prise a two-way cam 40 mounted on the insulated sub-base 41 by any suitable means. The arm 22 may have a lever 42 pivoted by means of pin 43 and this lever 42 may be provided with a roller 44 riding on the cam 40. A spring 45 may be attached by a hook 46 to the arm 22, and the other end of this spring may be attached to a threaded pin 47 passing through the bridge member 48 of the lever 42. A suitable knurled nut 49 may be provided to adjust the tension of the spring 45. It is thus seen that the tension of the spring 45 causes the roller 44 to ride on the cam 40 and provides a snap action for the lever 22.

60 Contact points may be connected and disconnected by the operation of the snap action. As herein shown, this may be accomplished by having the cam 40 pivoted at the pin 50. It may have an extension 51 upon which the contact points 52 are mounted and to which the lead 53 is connected. Another contact point 54 may be mounted on the insulated sub-base 41. Thus it is seen that the passing of the roller 44 over the dividing point of the cam 40 causes the contact points 52 to snap to and away from the contact point 54. A suitable upward limit pin 55 may be provided for the extension 51 of the cam 40. If desired, the contact points 52 may be of the arc breaker type, in which the resistance contact piece 52a is the first and last to make or break the circuit.

65 The arm 22 may be provided with means for limiting its movement. As an example, an extension 55 may be provided on the arm, and extension 56 may be made integral with platform 108.

70 During the normal operation of the switch, the platform 108 rests on the platform 105. However, if abnormal excessive pressures should be created in the pipe 21 the expansion member 20 would first cause the lever 22 to contact with extension 56. If further pressure should be created, the upward movement of the member 25 would cause the platform 108 to be lifted through the medium of the ears 28 and extension 56 from the platform 105. The springs 110 would provide the necessary yielding play in the platform 108. Since the strength of these springs 110 is sufficient to keep the platforms 105 and 108 normally in contact, the action of the switch would be regular except during such abnormal pressures as have been heretofore described. The abnormal pressures only would have the necessary strength to flex the springs 110 from their normal positions. In the embodiment shown the excessive pressures are due directly to refrigerant pressures. The excessive pressures, however, may be caused also indirectly, as by the excessive pressures in a warm thermostatic bulb operating the pressure-responsive element.

75 The adjustments provided by rod 30 and pin 47 are related, but are for different pur-

poses. Rod 30 tends to provide adjustment of the mean pressure at which the switch operates, while pin 47 tends to separate the pressure limits at which the switch operates.

5 That is, rod 30 varies the value of the mean pressure of operation, while pin 47 varies the difference between upper and lower limits of operation. The tension on lever 42 determines the resistance to the snap action.

10 The position shown in Fig. 2 is the one immediately after the circuit closing snap action. Should pressures continue to rise in bellows 20 the roller 44 would continue downwardly until the arm 22 would abut the extension 56. A further increase in pressure would then begin to lift the platform 108 until the top of the bellows, such as plate 23, would abut the platform 105. The slight lifting of the roller 44 caused by the lifting of 15 the platform 108 is insufficient to cause a circuit breaking snap action. This slight lift is not sufficient to carry the roller past the divider of the two-way cam 40. Any further pressure would then be carried by the plate 20 23 and platform 105 and no further strain would be placed on the operating lever mechanism. Because of the broad surface of contact at plate 23, the abnormal pressures do not deform the bellows. Since the platform 25 105 takes the load of abnormal pressures, the lever system is not damaged.

30 While the form of embodiment of the invention as herein disclosed, constitutes a preferred form, it is to be understood that other forms might be adopted, all coming within the scope of the claims which follow.

What is claimed is as follows:

1. The combination, in controlling apparatus, of a member adapted to be moved from one position to another, a pressure responsive device connected to said member, a pivot for said member, and means for moving said pivot only during abnormal movement of said pressure responsive device.
- 45 2. Switch operating mechanism including a yieldable support, an operating lever pivoted to said support, a pressure responsive device connected to said lever, a stop on said support for limiting the movement of said lever, said support being yieldable during abnormal expansion of said pressure responsive device to permit movement of said stop member.
- 50 3. The combination, in controlling apparatus of a member adapted to be moved from one position to another, and pressure responsive device operatively connected to said member, a yieldable support for said member including a plurality of plates, one of said plates being movable with respect to the other, a stop member on said one of said plates and a spring member normally holding said plates together, said spring member 55 permitting movement of said movable plate

and said stop member only upon abnormal expansion of said pressure responsive device. In testimony whereof I hereto affix my signature.

OTTO M. SUMMERS.
